ABSTRACT OF THE DISCLOSURE

Racemic mixtures of a compound of the formula

wherein

R is alkyl of 1 to 5 carbon atoms,

R₁ is cyano, carboxyl, hydroxyl, amino, nitro, trifluoromethyl, alkyl of up to 5 carbon atoms, alkenyl of up to 5 carbon atoms, alkinyl of up to 5 carbon atoms, alkoxy of up to 5 carbon atoms, alkenyloxy of up to 5 carbon atoms, alkyloxy of up to 5 carbon atoms, alkoxyalkyl of up to 5 carbon atoms, aminoalkyl of up to 5 carbon atoms, alkylaminoalkyl of up to 5 carbon atoms, dialkylaminoalkyl of up to 5 carbon atoms, alkylamino of up to 5 carbon atoms, cyano(alkyl of up to 5 carbon atoms), alkoxy of up to 5 carbon atoms)carbonyl, alkyl of up to 5 carbon atoms)amino-carbonyl, alkylthio of up to 5 carbon atoms, acyloxy of up to 5 carbon atoms, acylamino of up to 5 carbon atoms, aryl of up to 10 carbon atoms, aralkyl of up to 10 carbon atoms, aryloxy of up to 10 carbon atoms, aralkoxy of up to 10 carbon atoms, arylamino of up to 10 carbon atoms or halogen,

R₂ is hydrogen, halogen, cyano, alkyl of up to 5 carbon atoms, alkoxy of up to 5 carbon atoms or alkenyl of up to 5 carbon atoms,

R₁ and R₂, together with each other, are 3,4-methylenedioxy,

R₃ is hydrogen, halogen, alkyl of up to 5 carbon atoms or alkoxy of up to 5 carbon atoms, and n is an integer from 2 to 7, inclusive,

optically active components thereof, and non-toxic, pharmacologically acceptable acid addition salts of said racemic and optically active compounds, useful as β -adrenergic receptor blocking agents in warm-blooded animals.

This invention relates to novel 1-phenoxy-2-hydroxy-3-(cycloalkyl-amino)-propanes and their non-toxic acid addition salts, as well as to various methods of preparing these compounds.

More particularly, the present invention relates to racemic mixtures of a compound of the formula

2

wherein

R is alkyl of 1 to 5 carbon atoms,
R₁ is cyano, carboxyl, hydroxyl, amino, nitro, trifluoromethyl, alkyl of up to 5 carbon atoms, alkenyl of up to 5 carbon atoms, alkinyl of up to 5 carbon atoms, alkoxy of up to 5 carbon atoms, alkenyloxy of up to 5 carbon atoms, alkyloxy of up to 5 carbon atoms, alkoxyalkyl of up to 5 carbon atoms, aminoalkyl of up to 5 carbon atoms, alkylaminoalkyl of up to 5 carbon atoms, dialkylaminoalkyl of up to 5 carbon atoms, alkylamino of up to 5 carbon atoms, cyano(alkyl of up to 5 carbon atoms), alkoxy of up to 5 carbon atoms)carbonyl, (alkyl of up to 5 carbon atoms)amino-carbonyl, alkylthio of up to 5 carbon atoms, acyloxy of up to 5 carbon atoms, acylamino of up to 5 carbon atoms, aryl of up to 10 carbon atoms, aralkyl of up to 10 carbon atoms, aryloxy of up to 10 carbon atoms, aralkoxy of up to 10 carbon atoms, arylamino of up to 10 carbon atoms or halogen,

R₂ is hydrogen, halogen, cyano, alkyl of up to 5 carbon atoms, alkoxy of up to 5 carbon atoms or alkenyl of up to 5 carbon atoms,

R₁ and R₂, together with each other, are 3,4-methylenedioxy,

R₃ is hydrogen, halogen, alkyl of up to 5 carbon atoms or alkoxy of up to 5 carbon atoms, and n is an integer from 2 to 7, inclusive,

optically active components thereof, or non-toxic, pharmacologically acceptable acid addition salts of said racemic or optically active compounds.

The compounds according to the present invention may be prepared by a number of methods involving well known chemical principles, among which the following have proved to be particularly convenient and efficient.

Method A

By reacting a compound of the formula

(II)

wherein R₁, R₂ and R₃ have the same meanings as in Formula I and Z is

or $-\text{CHOH}-\text{CH}_2-\text{Hal}$, where Hal is halogen, with a cycloalkylamine of the formula

(III)

wherein R and n have the same meanings as in Formula I.

Method B

By reacting a compound of the Formula II with an N,N'-dicycloalkylurea of the formula

(IV)

wherein R and n have the same meanings as in Formula I. The reaction is preferably performed in a water-immiscible, high-boiling-point solvent, such as Tetralin, Decalin, benzonitrile or the like, or without a solvent in the molten state, at temperatures between 150 and 220°C., preferably at 180–200°C. Thus, this reaction is not practicable or can only be performed with difficulty, in those cases

where heat-sensitive groups (such as unsaturated groups, hydroxyl or amino groups) are present in the starting material.

Method C

By splitting off an easily removable protective group 5 from a compound of the formula

wherein R, R₁, R₂, R₃ and n have the same meanings as in Formula I and G is a hydrolytically easily removable group (for instance, an acyl or an acetal group).

Method D

By splitting off a protective group from a tertiary amine of the formula

wherein R, R₁, R₂, R₃ and n have the same meanings as in Formula I and Sch represents a hydrogenolytically or hydrolytically easily removable protective group, such as benzyl or acetyl.

Method E

By hydrolysis of an oxazolidinone of the formula

wherein R, R₁, R₂, R₃ and n have the same meanings as in Formula I, for example with a strong alkali in an aqueous or aqueous/alcoholic medium.

Method F

By hydrolysis or pyrolysis of a urea derivative of the formula

wherein R, R₁, R₂, R₃ and n have the same meanings as in Formula I, and R₄ and R₅ (which may be identical to or different from each other) are each hydrogen or alkyl (preferably lower alkyl), aralkyl (preferably benzyl), or aryl (preferably phenyl), in conventional fashion. The hydrolysis is carried out, for instance, with a strong base, such as aqueous KOH; on the other hand, the pyrolysis only be performed with good yields if there are no heat-sensitive groups present in the starting material.

Further possibilities for the production of the compounds of the Formula I are provided if the starting material wherein the 1-phenoxy-2-hydroxy-3-cycloalkylamino structure is already present, but wherein one of the substituents R₁ to R₃ is still missing or is only present in the form of a precursor, is converted by the introduction of the missing phenyl substituent or by conversion of the precursor of the phenyl substituent into the desired substituent R₁, R₂ or R₃ into the end product of the Formula I. Thus, for example:

Method G

Compounds of the formula

wherein R, R₁, R₂ and n have the same meanings as in Formula I and A is a group convertible by conventional methods into R₁, such as the aldehyde-(—CHO)-group (converts by reduction into —CH₂OH or CH₃), the —CONH₂ or —CH=NOH group (converts by dehydration into the cyano group), a halo-alkyl group (converts by reaction with ammonia or amines, water or aliphatic alcohols into an aminoalkyl, alkylaminoalkyl, dialkylaminoalkyl, hydroxyalkyl or alkoxyaryl group), a hydroxyl group (converts by etherification into an alkoxy group), a halogen atom (converts by reaction with Cu(I)CN and pyridine at elevated temperatures into a cyano group), a nitro group (converts by reduction into the amino group), an alkoxy carbonyl group (converts by saponification into a carboxyl group) or an amino group (converts by diazotization and heating with copper(I)-cyanide or copper(I)-halide into the cyano group or a halogen atom), may be converted into compounds of the Formula I, by using the conventional methods required for each case (dehydration, exchange reaction or condensation, alkylation, reduction, diazotization and heating with a copper-I-salt, etc.).

Method H

Likewise, compounds of the formula

wherein R, R₁ and R₃ and n have the same meanings as in Formula I and B represents a group convertible into R₂ in conventional manner, such as the hydroxyl or aldehyde (CHO) group or an amino group, or compounds of the formula

wherein R, R₁, R₂ and n have the same meanings as in Formula I and D represents a group convertible into R₃ in conventional manner (such as the aldehyde, hydroxyl or amino group), may be converted into compounds of the Formula I by using the conventional method required for each case (alkylation, reduction, diazotization and heating with a copper-I-salt, etc.).

Method I

For the preparation of those compounds wherein R₂ or R₃ represents halogen, a halogen substituent may be introduced into compounds of the formula

wherein R and n have the same meanings as in Formula I and Ar is

where R₁ and R₃ or R₁ and R₂ have the same meanings as in Formula I. his process may be carried out, for example, by reaction with a mixture of concentrated hy-

hydrogen peroxide and the corresponding hydrohalic acid at elevated temperatures.

Some of the starting materials required for methods A through I are known, while the others may be obtained according to the conventional processes. Thus, the epoxides of the Formula II may easily be prepared by reacting a corresponding phenol or phenolate of the formula

wherein R₁, R₂ and R₃ have the same meaning as in Formula I and Kt represents hydrogen or a cation (for example, an alkali metal cation). The epoxides, in turn, may be used for the preparation of further starting materials; for example, the halohydrins of the Formula II may be prepared by reaction of the epoxides with the corresponding hydrohalic acid.

The ureas of the Formula IV may be prepared, for example, by reaction of phosgene with amines of the Formula III. The latter, in turn, may be prepared starting from the corresponding carbinols according to the so-called Ritter reaction [see J.A.C.S. 70 (1948), 4048] by reaction with KCN in glacial acetic acid and cleavage of the formamide thus formed with KOH. Compounds of the Formula V may be obtained by reacting a halohydrin of the Formula II with a compound which forms the protective group G, such as vinyl ether or dihydropyran, and subsequently reacting the obtained compound of the formula

wherein R₁, R₂, R₃, Hal and G have the meanings previously defined, with an amine of the Formula III. The tertiary amines of the Formula VI are obtained by reacting a compound of the Formula XIII with a compound of the formula

wherein R, Sch, Z and n have the meanings previously defined. The oxazolidinones of the Formula VII may, for instance, be prepared, starting from the epoxides of the Formula II, by reacting the latter with a urethane (from ethyl chloroformate and an alkylamine of the Formula III) of the formula

wherein R and n have the same meanings as in Formula I. A urea derivative of the Formula V may, for instance, be obtained according to the method described in Chem. Abstr. 58, page 3337c, by reacting an epoxide of the Formula II with the corresponding urea derivative (for instance, with a compound of the Formula IV). The compounds of the Formulas IX to XII already comprise the 1-phenoxy-2-hydroxy-3-cycloalkylaminopropane structure and may, therefore, be prepared analogous to method A described above, starting from the corresponding phenol, via the corresponding 1-phenoxy-2,3-epoxypropane (producible therefrom by reaction with epichlorohydrin) by reaction with a cycloalkylamine of the Formula III.

The compounds according to the present invention comprise an asymmetric carbon atom in the CHOH-group and therefore occur as racemates as well as in the form of optical antipodes. The latter may be obtained not only by means of separation of racemates with the usual auxiliary acids, such as dibenzoyl-D-tartaric acid or D-3-bromocamphor-8-sulfonic acid, but also by using the corresponding optically active starting material.

The 1-phenoxy-3-cycloalkylamino-propanols of the Formula I according to the invention may be converted into non-toxic pharmaceutically acceptable acid addition salts in conventional fashion. Examples of such salts are, for instance, those formed with hydrochloric acid, hydrobromic acid, sulfuric acid, methane-sulfonic acid, maleic acid, acetic acid, oxalic acid, lactic acid, tartaric acid, 8-chlorotheophylline or the like.

The following examples further illustrate the present invention and will enable others skilled in the art to understand it more completely. It should be understood, however, that the invention is not limited solely to the particular examples given below.

EXAMPLE 1

1-(2'-cyano-phenoxy)-2-hydroxy-3-(1"-methylcyclohexylamino)-propane hydrochloride

8.75 gm. (0.05 mol) of 1-(2'-cyanophenoxy)-2,3-propane-epoxide were dissolved in 100 ml. of ethanol, and 25 ml. of a 2 M solution of 1-methylcyclohexylamine were added. After two hours of refluxing the solvent was distilled off, and the residue was treated with 200 ml. of water. The aqueous mixture was acidified with HCl, heated to 60° C. and separated from insoluble matter. The cooled aqueous phase was made alkaline with NaOH after extraction with ether, and the precipitated base was extracted with ether. The organic phase was washed with water and dried over MgSO₄. After distilling off the ether, the remaining crystalline base was recrystallized from ethylacetate by addition of petroleum ether. The dry substance was dissolved in a little acetonitrile, ethereal HCl was added, and the crystalline hydrochloride was collected by vacuum filtration. Yield: 5.8 gm., M.P. 163-165° C.

EXAMPLE 2

1-(2'-cyanophenoxy)-2-hydroxy-3-(1"-methylcyclopentylamino)-propane hydrochloride

7.8 gm. (0.045 mol) of 1-(2'-cyanophenoxy)-2,3-propaneepoxide were dissolved in 100 ml. of methanol, 5.5 gm. (0.055 mol) of 1-methylcyclopentylamine were added, and the mixture was refluxed for three hours. After distilling off the solvent, the residue was treated with 1 N, HCl, and insoluble matter was filtered off. After extracting the aqueous phase with ether, the former was made alkaline with NaOH, and the precipitated base was taken up in ether. The organic phase was washed with water and dried over MgSO₄. After distilling off the ether, the crystalline base was dissolved in ethanol, ethereal HCl was added, and the precipitated hydrochloride was collected by vacuum filtration and recrystallized from ethanol by addition of ether. Yield: 4.5 gm., M.P. 132-134° C.

EXAMPLE 3

1-(2'-bromophenoxy)-2-hydroxy-3-(1"-methyl-cyclopentylamino)-propane hydrochloride

5 gm. (0.05 mol) of 1-methylcyclopentylamine were added to a solution of 7.5 gm. (0.033 mol) of 1-(2'-bromophenoxy)-2,3-propaneepoxide in 80 ml. of ethanol, and the mixture was refluxed for two hours. After distilling off the ethanol in vacuo, the residue was dissolved in a little ethanol, and ethereal HCl was added. The crystalline substance precipitated thereby was recrystallized from ethanol by addition of ether. Yield: 8.2 gm., M.P. 156-157° C.

EXAMPLE 4

1-(2'-chloro-5'-methylphenoxy)-2-hydroxy-3-(1"-methylcyclopentylamino)-propane hydrochloride

8 gm. (0.04 mol) of 1-(2'-chloro-5'-methylphenoxy)-2,3-propaneepoxide were dissolved in 80 ml. of ethanol, 5 gm. (0.05 mol) of 1-methylcyclopentylamine were added, and the mixture was refluxed for two hours. After distilling off the solvent in vacuo, the residue was dissolved in ethanol, and the solution was acidified with ethereal HCl. The isolated crystalline product was recrystallized from ethanol by addition of ether. Yield: 8.2 gm., M.P. 170-172° C.

EXAMPLE 5

1-(2'-bromophenoxy)-2-hydroxy-3-(1"-methylcyclohexylamino)-propane hydrochloride

4.5 gm. (0.04 mol) of 1-methyl-cyclohexylamine were added to a solution of 6.9 gm. (0.03 mol) of 1-(2'-bromophenoxy)-2,3-propaneepoxide in 80 ml. of ethanol, and the mixture was refluxed for two hours. The residue remaining after distilling off the solvent in vacuo was dissolved in ethanol, and ethereal HCl was added. The precipitated hydrochloride was recrystallized from ethanol/ether. Yield: 5.2 gm., M.P. 157-158° C.

EXAMPLE 6

1-(2'-propargyloxyphenoxy)-2-hydroxy-3-(1"-methylcyclohexylamino)-propane hydrochloride

6.1 gm. (0.03 mol) of 1-(2'-propargyloxyphenoxy)-2,3-propaneepoxide were dissolved in 75 ml. of ethanol, 4.5 gm. (0.04 mol) of 1-methylcyclohexylamine were added, and the mixture was boiled for two hours. Then, the solvent was distilled off, the residue was dissolved in ethanol, and the solution was acidified with ethereal HCl. The crystalline hydrochloride was collected and recrystallized from ethanol by addition of ether. Yield: 6.2 gm., M.P. 137-138° C.

EXAMPLE 7

1-(2'-allyloxyphenoxy)-2-hydroxy-3-(1"-methylcyclohexylamino)-propane oxalate

6.2 gm. (0.03 mol) of 1-(2'-allyloxyphenoxy)-2,3-propaneepoxide were dissolved in 60 ml. of ethanol, 4.5 gm. (0.04 mol) of 1-methylcyclohexylamine were added, and the mixture was refluxed for two hours. After distilling off the solvent, the residue was dissolved in ether, and an ethereal solution of oxalic acid was added. The crystalline oxalate was recrystallized from ethanol by addition of ether. Yield: 5.9 gm., M.P. 141-143° C.

EXAMPLE 8

1-(2'-ethinylphenoxy)-2-hydroxy-3-(1"-methylcyclopentylamino)-propane hydrochloride

7.5 gm. (0.04 mol) of 1-(2'-ethinylphenoxy)-2,3-epoxypropane were dissolved in 80 ml. of ethanol, 5 gm. (0.05 mol) of 1-methylcyclopentylamine were added, and the mixture was refluxed for 2.5 hours. The residue remaining after distilling off the solvent was dissolved in ethanol, and ethereal HCl was added. The colorless crystalline precipitate was recrystallized from ethanol/ether. Yield: 6.7 gm., M.P. 171-173° C.

EXAMPLE 9

1-(2'-bromophenoxy)-2-hydroxy-3-(1"-methylcycloheptylaminio)-propane hydrochloride

6.9 gm. (0.03 mol) of 1-(2'-bromophenoxy)-2,3-propaneepoxide were dissolved in 75 ml. of ethanol, 5 gm. (0.04 mol) of 1-methylcycloheptylamine were added, and the mixture was refluxed for two hours. The residue remaining after distilling off the solvent in vacuo was dissolved in ethanol, and the solution was acidified with

ethereal HCl. The solid hydrochloride precipitated thereby was recrystallized from ethanol by addition of ether. Yield: 6.4 gm., M.P. 167-168° C.

EXAMPLE 10

5 Analogous to Example 4, 1-(2'-chloro-5'-methylphenoxy)-2-hydroxy-3-(1"-methylcyclohexylamino)-propane hydrochloride was prepared from 1-(2'-chloro-5'-methylphenoxy)-2,3-epoxypropane and 1-methyl-cyclohexylamine. The HCl addition salt was obtained by dissolution of the base in ethanol and acidifying the solution with ethereal HCl. M.P. 174-177° C.

EXAMPLE 11

15 Analogous to Example 4, 1-(2'-chloro-5'-methylphenoxy)-2-hydroxy-3-(1"-ethylcyclohexylamino)-propane hydrochloride was prepared by reacting 1-(2'-chloro-5'-methylphenoxy)-2,3-epoxypropane with 1-ethylcyclohexylamine. M.P. of the HCl addition salt (obtained from the base as in Example 4): 179-180° C.

EXAMPLE 12

25 Analogous to Example 1, 1-(2'-cyanophenoxy)-2-hydroxy-3-(1"-ethylcyclohexylamino)-propane hydrochloride was obtained from 1-(2'-cyanophenoxy)-2,3-epoxypropane and 1-ethylcyclohexylamine. The HCl addition salt, obtained as in Example 1, melted at 157-158° C.

EXAMPLE 13

30 Analogous to Example 6, 1-(2'-propargyloxyphenoxy)-2-hydroxy-3-(1"-methylcyclopentylamino)-propane hydrochloride was obtained from 1-(2'-propargyloxyphenoxy)-2,3-epoxypropane and 1-methylcyclopentylamine. M.P. of the HCl salt: 167-168° C.

EXAMPLE 14

35 Analogous to Example 7, 1-(2'-allyloxyphenoxy)-2-hydroxy-3-(1"-methylcyclohexylamino)-propane hydrochloride was prepared from 1-(2'-allyloxyphenoxy)-2,3-epoxypropane and 1-methylcyclohexylamine. M.P. of the HCl addition salt: 110-111° C.

EXAMPLE 15

40 Analogous to Example 8, 1-(2'-ethinylphenoxy)-2-hydroxy-3-(1"-methylcyclohexylamino)-propane hydrochloride was prepared from 1-(2'-ethinylphenoxy)-2,3-epoxypropane and 1-methylcyclohexylamine. M.P. of the HCl addition salt: 184-185° C.

EXAMPLE 16

45 Analogous to Example 1, 1-(2'-methyl-4'-cyanophenoxy)-2-hydroxy-3-(1"-methylcyclohexylamino)-propane hydrochloride was prepared from 1-(2'-methyl-4'-cyanophenoxy)-2,3-epoxypropane and 1-methylcyclohexylamine. M.P. of the HCl addition salt: 206-207° C.

EXAMPLE 17

50 Analogous to Example 1, 1-(2'-cyanophenoxy)-2-hydroxy-3-(1"-isopropylcyclohexylamino)-propane hydrochloride was prepared by reacting 1-(2'-cyanophenoxy)-2,3-epoxypropane with 1-isopropylcyclohexylamine. The hydrochloride, obtained by dissolution of the base in ethanol and acidifying the solution with ethereal HCl, melted at 200-201° C.

EXAMPLE 18

55 Analogous to Example 4, 1-(2'-chloro-5'-methylphenoxy)-2-hydroxy-3-(1"-methylcycloheptylaminio)-propane hydrochloride was prepared from 1-(2'-chloro-5'-methylphenoxy)-2,3-epoxypropane and 1-methylcycloheptylamine. The hydrochloride was obtained from the base by acidification with ethereal HCl. M.P. 191-194° C.

9
EXAMPLE 19

Analogous to Example 1, 1-(2'-hydroxymethylphenoxy) - 3 - (1" - methylcycloheptylamino)-propane hydrochloride was prepared from 1-(2-cyanophenoxy)-2,3-epoxypropane and 1-methylcycloheptylamine. The hydrochloride had a melting point of 160-161° C.

EXAMPLE 20

1 - (2' - propargyloxyphenoxy) - 2 - hydroxy-3-(1" - methylcycloheptylamino)-propane hydrochloride was prepared from 1 - (2' - propargyloxyphenoxy)-2,3-propaneeoxide and 1-methylcycloheptylamine. Dissolution of the base in ethanol and acidification of the solution with ethereal HCl yielded the HCl addition salt, M.P. 110-111° C.

EXAMPLE 21

1 - (2' - allylphenoxy) - 2 - hydroxy-3-(1" - methylcycloheptylamino)-propane hydrochloride was prepared from 1 - (2' - allylphenoxy) - 2,3 - epoxypropane and 1-methylcycloheptylamine, analogous to Example 7. The hydrochloride had a melting point of 124-126° C.

EXAMPLE 22

Analogous to Example 7, 1-(2'-allyloxyphenoxy)-2-hydroxy - 3 - (1" - methylcycloheptylamino)-propane hydrochloride was prepared from 1-(2'-allyloxyphenoxy)-2,3-epoxypropane and 1-methylcycloheptylamine. M.P. of the hydrochloride: 97-99° C.

EXAMPLE 23

Analogous to Example 7, 1-(2'-allyloxyphenoxy)-2-hydroxy - 3 - (1" - methylcyclopentylamino)-propane oxalate was prepared from 1-(2'-allyloxyphenoxy)-2,3-epoxypropane and 1-methylcyclopentylamine. The free base was dissolved in ethanol, and the solution was acidified with an ethereal solution of oxalic acid, yielding the oxalate, M.P. 100-101° C.

EXAMPLE 24

Analogous to Example 1, 1-(2'-hydroxymethylphenoxy) - 2 - hydroxy - 3 - (1" - methylcyclohexyl)-amino-propane oxalate was prepared from 1-(2'-hydroxymethylphenoxy) - 2,3 - epoxypropane and 1-methylcyclohexylamine. The oxalate melted at 211-212° C.

EXAMPLE 25

1-(2'-cyano-4'-chlorophenoxy)-2-hydroxy-3-(1" - methylcyclohexylamino)-propane · HCl

2.2 gm. (0.0066 mol) of 1-(2'-cyanophenoxy)-2-hydroxy-3-(1" - methylcyclohexylamino)-propane hydrochloride (prepared according to Example 1) were dissolved in 15 ml. of concentrated HCl, and the solution was heated to 45° C., whereupon 0.75 gm. (0.066 mol) of 30% hydrogen peroxide was added dropwise to the solution over a period of five minutes; the temperature rose to 65° C. The reaction mixture was then stirred for 1/2 hour at 65° C. and then cooled. The product crystallized out. Yield: 1.6 gm.; M.P. (hydrochloride): 194-196° C.

EXAMPLE 26

1-(2'-cyanophenoxy)-2-hydroxy-3-(1" - methylcyclohexylamino)-propane · HCl

19.5 gm. (0.1 mol) of 1-(2'-cyanophenoxy)-2,3-epoxypropane were dissolved in 100 ml. of alcohol, and the solution was admixed with 13.5 gm. (0.12 mol) of 1-methylcyclohexylamine. The mixture was refluxed for two hours, and subsequently the solvent was distilled off. The residue was recrystallized twice from ethylacetate by addition of petroleum ether having a boiling point of 40° C. Yield: 20.4 gm. 5 gm. of the base were converted with ethereal hydrochloric acid into the hydrochloride. Yield (after recrystallization from alcohol/ether): 4.6 gm.; M.P. (hydrochloride): 166-168° C.

10
EXAMPLE 27

1-(2'-aminophenoxy)-2-hydroxy-3-(1" - methylcyclohexylamino)-propane · 2 HCl

15.4 gm. (0.05 mol) of 1-(2'-cyanophenoxy)-2-hydroxy-3-(1" - methylcyclohexylamino)-propane base, prepared according to Example 26, were dissolved in methanol and hydrogenated, with Raney-nickel as a catalyst, at normal pressure. After separating the catalyst by vacuum-filtration and distilling off the solvent, the residue was converted into the dihydrochloride by means of ethereal HCl, which was recrystallized twice from ethanol by addition of ether. Yield: 3.6 gm.; M.P. (dihydrochloride): 235-237° C.

EXAMPLE 28

1-(2'-bromophenoxy)-2-hydroxy-3-(1" - methylcyclohexylamino)-propane hydrochloride

1.16 gm. (0.00375 mol) of 1-(2'-bromophenoxy)-2-hydroxy-3-bromopropane were heated in Tetralin with 1.8 gm. (0.0075 mol) of N,N'-bis-(1-methylcyclohexyl)-urea for two hours at 180-220° C. After cooling, 50 ml. of ether were added, and by extraction with 1 N HCl the basic components were extracted. The aqueous phase was extracted with ether and made alkaline with NaOH. The precipitated basic components were taken up in ether, and the ether phase was washed with water and dried over MgSO₄. After distilling off the ether, a residue remained which was dissolved in a little ethanol, and the solution was admixed with ethereal HCl. The precipitated crystals were separated and dried. Yield: 300 mgm.; M.P. 154-156° C.

EXAMPLE 29

1-(2'-bromophenoxy)-2-hydroxy-3-(1" - methylcyclohexylamino)-propane hydrochloride

The tetrahydropyranyl ether obtained from 7.25 gm. (0.025 mol) of 1-(2'-bromophenoxy)-2-hydroxy-3-bromopropane, 2.52 gm. (0.03 mol) of dihydropyran and 10 gm. of p-toluenesulfonic acid at 50° C. was dissolved in 50 ml. of ethanol, 8.5 gm. (0.075 mol) of 1-methylcyclohexylamine were added to the solution, and the mixture was refluxed for six hours. After distilling off the solvent, the residue was dissolved in a little acetone, and upon addition of maleic acid to the solution, the maleate was obtained. 2 gm. of the maleate were heated in 25 ml. of 2 N HCl on a water bath for ten minutes. After cooling, the solution was extracted with ether. The aqueous phase was made alkaline with NaOH, and the precipitated base was taken up in ether. The ether solution was washed, dried, and the ether was distilled off. The hydrochloride was obtained by dissolving the residue in a little ethanol and adding ethereal HCl to the solution. Yield: 150 mgm.; M.P. 153-157° C.

EXAMPLE 30

1-(2'-methyl-4'-cyanophenoxy)-2-hydroxy-3-(1" - methylcyclohexylamino)-propane hydrochloride

0.75 gm. of 1-(2'-methyl-4'-cyanophenoxy)-2-hydroxy-3-[N-acetyl-(1-methylcyclohexylamino)]-propane was refluxed in 20 ml. of ethanol with 0.3 gm. of KOH for two hours. After distilling off the solvent, water was added, and the aqueous mixture was extracted with ether. The organic phase was washed with water and dried over MgSO₄. After evaporation of the ether, the residue was dissolved in a little ethanol, ethereal HCl was added, and the crystalline hydrochloride was collected by vacuum filtration. Yield: 0.3 gm.; M.P. 204-206° C.

EXAMPLE 31

1-(2'-methyl-4'-cyanophenoxy)-2-hydroxy-3-(1" - methylcyclohexylamino)-propane hydrochloride

1.1 gm. of 3-(1" - methylcyclohexyl)-5-(2'-methyl-4'-cyanophenoxyethyl)-oxazolidinone were refluxed in 20 ml. of ethanol and 4 ml. of water with 0.6 gm. of KOH

for 90 minutes. After distilling off the solvent, water was added, and the aqueous mixture was extracted with ether. The ether phase was washed with water and dried over $MgSO_4$. After distilling off the ether, the residue was dissolved in a little ethanol, ethereal HCl was added, and the precipitated hydrochloride was collected. Yield: 0.28 gm.; M.P. 202-206° C.

EXAMPLE 32

1-(2'-cyanophenoxy)-2-hydroxy-3-(1"-methylcyclohexylamino)-propane hydrochloride

A diazonium salt solution, prepared from 3.52 gm. (0.01 mol) of 1-(2'-aminophenoxy)-2-hydroxy-3-(1"-methylcyclohexylamino)-propane·2HCl, 4 ml. of concentrated HCl, 20 ml. of water and an aqueous solution of 1.4 gm. (0.02 mol) of $NaNO_2$, was slowly added dropwise to a hot solution of 5 gm. of copper sulfate, 5.8 gm. of copper cyanide in 30 ml. of water. After stirring the mixture for 30 minutes at 90° C., it was cooled and made alkaline with NaOH. After addition of chloroform, the insoluble components were separated. The organic phase was isolated, washed with water and dried over $MgSO_4$. After distilling off the $CHCl_3$, the residue was dissolved in ethanol, and ethereal HCl was added. The crystals precipitated thereby were recrystallized once more from ethanol by addition of ether. Yield: 950 mgm.; M.P. 161-164° C.

EXAMPLE 33

Analogous to Example 1, 1-(2'-cyano-5'-methylphenoxy)-2-hydroxy - 3 - (1"-methylcyclohexylamino)-propane was prepared from 1-(2'-cyano-5'-methylphenoxy)-2,3-propanepoxide and 1-methylcyclohexylamine in ethanol. M.P. (hydrochloride): 173-176° C.

EXAMPLE 34

Analogous to Example 1, 1-(2-cyano-5-methylphenoxy)-2-hydroxy - 3 - (1-methylcycloheptylamino)-propane was prepared from 1-(2-cyano-5-methylphenoxy)-2,3-propanepoxide and 1-methylcycloheptylamine in ethanol while refluxing. M.P. (hydrochloride): 192-194° C.

EXAMPLE 35

Analogous to Example 1, 1-(2'-cyano-5'-methylphenoxy)-2-hydroxy - 3 - (1"-methylcyclopentylamino)-propane was prepared from 1-(2'-cyano-5-methylphenoxy)-2,3-propanepoxide and 1-methylcyclopentylamine. M.P. (hydrochloride): 143-146° C.

EXAMPLE 36

1-(2'-chloro-5'-methylphenoxy)-2-hydroxy-3-(1"-methylcyclopentylamino)-propane hydrochloride

1.9 gm. (0.005 mol) of N-isopropyl-N'-(1'-methylcyclopentyl)-N"-[2"-hydroxy-3"- (2"-chloro - 5'" - methylphenoxy)-propyl]-urea, 15 ml. of Tetralin and 100 mgm. of LiCl were combined, and the mixture was heated at 200° C. for one hour. Thereafter, the reaction mixture was diluted with ether and extracted twice with 10 ml. of 1 N HCl each. The combined HCl phases were washed once with a little ether and made alkaline with NaOH. The precipitated oil was taken up in ether. After washing with water and drying with $MgSO_4$, the ether was distilled off, the remaining oil was dissolved in ethanol, and the solution was acidified with ethanolic HCl. After addition of ether the product crystallized out. M.P. 170-172° C.; yield: 600 mgm.

EXAMPLE 37

1-(2'-cyanophenoxy)-2-hydroxy-3-(1"-methylcyclohexylamino)-propane hydrochloride

3.52 gm. (0.01 mol) of 1-(2'-aminophenoxy) - 2 - hydroxy-3-(1"-methylcyclohexylamino)-propane hydrochloride were dissolved in a mixture of 20 ml. of water and 4 ml. of concentrated HCl, and then a solution of

1.4 gm. (0.02 mol) of $NaNO_2$ in 5 ml. of water was slowly added dropwise to the solution. By exterior cooling with ice the temperature was kept between 9° and +5° C. After the addition was finished, the temperature of the combined solution was kept at about 0° C. for 15 minutes more. 5 gm. of $CuSO_4 \cdot 5H_2O$ (0.02 mol), 5.8 gm. of KCN (0.04 mol) and 30 ml. of water were combined and, while stirring, the mixture was heated to 90° C. The diazonium solution was stirred into the hot $Cu(I)CN$ -solution, and the batch was kept for 30 minutes at 90° C. After cooling and adding aqueous 10% NaOH, the reaction mixture was extracted with chloroform. The chloroform extract was washed with water, dried with $MgSO_4$ and evaporated. The residue was dissolved in ethanol, and the solution was acidified with ethanolic HCl. After addition of ether, the product crystallized out. After recrystallization from alcohol-ether, 950 mgm. of the product were obtained. M.P. 161-163° C.

EXAMPLE 38

1-(2'-cyano-5'-methylphenoxy)-2-hydroxy-3-(1"-methylcyclohexylamino)-propane hydrochloride

2.92 gm. (0.01 mol) of 1-(2'-amino-5'-methylphenoxy)-2-hydroxy-3-(1"-methylcyclohexylamino)-propane were dissolved in a mixture of 20 ml. of water and 6 ml. of HCl. Thereafter, a solution of 1.4 gm. (0.02 mol) of $NaNO_2$ in 5 ml. of water was slowly added dropwise to the amine solution, while stirring. By exterior cooling with ice the temperature was kept between 0° and +5° C. After the addition was finished the mixed solution was kept at about 0° C. for 15 minutes more. 5 gm. of

$CuSO_4 \cdot 5H_2O$

35 (0.02 mol), 5.8 gm. of KCN (0.09 mol) and 30 ml. of H_2O were combined and heated to 90° C. while stirring. The diazonium solution was added dropwise to the hot $Cu(I)CN$ -solution while stirring, and the batch was allowed to react for 30 minutes at 90° C. After cooling and adding aqueous 10% NaOH, the reaction mixture was extracted with chloroform. The chloroform extract was washed with water, dried with $MgSO_4$ and evaporated. The residue was dissolved in acetonitrile, and the solution was acidified with ethanolic HCl. The hydrochloride which crystallized out was recrystallized once more acetonitrile. M.P. 170-173° C.; yield: 500 mgm.

The compounds according to the present invention, that is, those embraced by Formula I above and their non-toxic, pharmacologically acceptable acid addition salts, have useful pharmacodynamic properties. More particularly, the compounds of the instant invention exhibit very effective β -adrenergic receptor blocking activities in warm-blooded animals, such as guinea pigs, and are therefore useful therapeutics for the treatment and prophylaxis of diseases of the coronaries and for the treatment of cardiac arrhythmia, especially tachycardia. The compounds also exhibit effective hypotensive activities.

Particularly effective as β -adrenergic receptor blocking agents are those compounds of the Formula I wherein 60 R is methyl; R_2 and R_3 are hydrogen or also alkyl; R_1 is an unsaturated group, such as ethinyl, cyano, allyl or allyloxy (especially in 2-position with respect to the proposed chain), or hydroxy-methyl; and n is 4, 5 or 6; and their non-toxic acid addition salts. In addition, compounds of the Formula I wherein R is methyl, R_1 is halogen, R_2 is hydrogen or methyl, R_3 is hydrogen and n is 4, 5 or 6, and their non-toxic acid addition salts are also very strong β -adrenergic receptor blocking agents. Among these, the following specific compounds and their non-toxic acid addition salts are of special interest:

1-(2'-ethinylphenoxy)-2-hydroxy-3-(1"-methylcyclopentylamino)-propane;
1-(2'-cyanophenoxy)-2-hydroxy-3-(1"-methylcyclopentylamino)-propane;

75

13

1-(2'-cyanophenoxy)-2-hydroxy-3-(1"-methylcyclohexyl-amino)-propane;
 1-(2'-chloro-5'-methylphenoxy)-2-hydroxy-3-(1"-methylcyclopentyl-amino)-propane;
 1-(2'-hydroxymethylphenoxy)-2-hydroxy-3-(1"-methylcyclohexyl-amino)-propane; and
 1-(2'-bromophenoxy)-2-hydroxy-3-(1"-methylcycloheptyl-amino)-propane.

1-(2'-cyanophenoxy)-2-hydroxy-3-(1"-methylcyclopentyl-amino)-propane is especially interesting due to its pronounced isoproterenol-antagonistic action with virtually complete absence of direct brady-cardiac action. Compounds of the Formula I wherein the phenyl group is substituted with a cyano group in 2-position and simultaneously with a lower alkyl (preferably methyl) group in 5-position are also especially effective; for instance,

1-(2'-cyano-5'-methylphenoxy)-2-hydroxy-3-(1"-methylcyclopentylamino)-propane,
 1-(2'-cyano-5'-methylphenoxy)-2-hydroxy-3-(1"-methylcyclohexylamino)-propane, and
 1-(2'-cyano-5'-methylphenoxy)-2-hydroxy-3-(1"-methylcycloheptylamino)-propane

and the non-toxic, pharmaceutically acceptable acid addition salts thereof.

For pharmaceutical purposes the compounds according to the present invention are administered to warm-blooded animals perorally or parenterally as active ingredients in customary dosage unit form consisting essentially of an inert pharmaceutical carrier and one effective dosage unit of the active ingredient, such as tablets, coated pills, capsules, wafers, powders, solutions, suspensions, emulsions, syrups, suppositories and the like. Such dosage unit compositions may, in addition to a compound of the present invention, also comprise an effective dosage unit of one or more compounds having a different pharmacodynamic property, such as a coronary dilator, a sympathomimetic, a cardiac glycoside and/or a tranquilizer. One effective dosage unit of the compounds according to the present invention is from 0.0166 to 5.0 mgm./kg. body weight, preferably 0.083 to 1.67 mgm./kg. (perorally) and 0.0166 to 0.34 mgm./kg. (parenterally).

The following examples illustrate a few dosage unit compositions comprising a compound of the present invention as an active ingredient and represent the best modes contemplated of putting the invention into practical use. The parts are parts by weight unless otherwise specified.

EXAMPLE 39

Tablets

The tablets composition was compounded from the following ingredients:

Parts	
1-(2'-cyanophenoxy)-2-hydroxy-3-(1"-methylcyclopentylamino)-propane·HCl	40.0
Corn starch	164.0
Secondary calcium phosphate	240.0
Magnesium stearate	1.0
Total	445.0

Preparation: The individual components were intimately admixed with each other, the mixture was granulated in customary fashion, and the granulate was compressed into 445 mgm.-tablets with a conventional tablet making machine. Each tablet contained 40 mgm. of the propanol salt and, when administered perorally to a warm-blooded animal of about 60 kg. body weight in need of such treat-

14

ment, produced a very effective β -adrenergic receptor blocking action.

EXAMPLE 40

Gelatin capsules

The capsule filler composition was compounded from the following ingredients:

	Parts
1-(2'-cyanophenoxy)-2-hydroxy-3-(1"-methylcyclohexylamino)-propane·HCl	25.0
Corn starch	175.0
Total	200.0

Preparation: The components were intimately admixed with each other, and 200 mgm.-portions of the mixture were filled into gelatin capsules of suitable size. Each capsule contained 25 mgm. of the propanol salt and, when perorally administered to a warm-blooded animal of about 60 kg. body weight in need of such treatment, produced a very effective β -adrenergic receptor blocking action.

EXAMPLE 41

Hypodermic solution

	Parts
1-(2'-chloro-5'-methylphenoxy)-2-hydroxy-3-(1"-methylcyclopentylamino)-propane·HCl	2.5
Sodium salt of EDTA (ethylenediaminetetraacetic acid)	0.2
Distilled water, q.s. ad 100.0 parts.	

Preparation: The propanol salt and the EDTA salt were dissolved in a sufficient amount of distilled water, and the solution was diluted to the desired volume with distilled water. The solution was filtered until free from suspended particles and filled into 1 cc. ampules under aseptic conditions. Finally, the ampules were sterilized and sealed. Each ampule contained 25 mgm. of the propanol salt, and when the contents thereof were intravenously administered to a warm-blooded animal of about 60 kg. body weight in need of such treatment, a very effective β -adrenergic receptor blocking action was produced.

EXAMPLE 42

Coated sustained release tablets

The tablet core composition was compounded from the following ingredients:

	Parts
1-(2'-ethinylphenoxy)-2-hydroxy-3-(1"-methylcyclopentylamino)-propane·HCl	25.0
Carboxymethyl cellulose (CMC)	295.0
Stearic acid	20.0
Cellulose acetate phthalate (CAP)	40.0
Total	380.0

Preparation: The propanol salt, the CMC and the stearic acid were intimately admixed with each other, and the mixture was granulated in customary fashion, using a solution of the CAP in 200 ml. of a mixture of ethanol and ethylacetate as the moistening agent. The granulate was then compressed into 380 mgm.-cores, which were coated in the usual way with an aqueous 5% solution of polyvinylpyrrolidone containing sugar. Each coated tablet contained 25 mgm. of the propanol salt and, when administered perorally to a warm-blooded animal of about 60 kg. body weight in need of such treatment, produced a very effective β -adrenergic receptor blocking action over an extended period of time.

15

EXAMPLE 43

Tablets with combination of active ingredients

The tablet composition was compounded from the following ingredients:

	Parts
1-(2'-hydroxymethylphenoxy) - 2 - hydroxy-3-(1''-methylcyclohexylamino)-propane · HCl	35.0
2,6 - bis - (diethanolamino) - 4,8 - dipiperidino-pyrimido-[5,4-d]-pyrimidine	75.0
Lactose	164.0
Corn starch	194.0
Colloidal silicic acid	14.0
Polyvinylpyrrolidone	6.0
Magnesium stearate	2.0
Soluble starch	10.0
Total	500.0

Preparation: The propanol salt, the lactose, the corn starch, the colloidal silicic acid and the polyvinylpyrrolidone were intimately admixed with each other, and the mixture was granulated in the usual way, using an aqueous solution of the soluble starch as the moistening agent. The granulate was admixed with magnesium stearate, and the composition was compressed into 500 mgm.-tablets. Each tablet contained 35 mgm. of the propanol salt and 75 mgm. of the pyrimidopyrimidine compound and, when perorally administered to a warm-blooded animal of about 60 kg. body weight in need of such treatment, produced very effective β -adrenergic receptor blocking and coronary dilating actions.

Analogous results were obtained when any one of the other compounds embraced by Formula I or a non-toxic acid addition salt thereof was substituted for the particular salt in Examples 39 through 43. Likewise, the amount of active ingredient in these illustrative examples may be varied to achieve the dosage unit range set forth above, and the amounts and nature of the inert pharmaceutical carrier ingredients may be varied to meet particular requirements.

While the present invention has been illustrated with the aid of certain specific embodiments thereof, it will be readily apparent to others skilled in the art that the invention is not limited to these particular embodiments, and that various changes and modifications may be made without departing from the spirit of the invention or the scope of the appended claims.

16

We claim:

1. A compound of the formula

wherein

 R_1 is cyano, R_2 is hydrogen or methyl, and n is 4, 5 or 6,

or a non-toxic, pharmacologically acceptable acid addition salt thereof.

2. A compound according to claim 1, which is 1-(2'-cyanophenoxy)-2-hydroxy - 3 - (1'' - methylcyclopentylamino)-propane or a non-toxic pharmaceutically acceptable acid addition salt thereof.

3. A compound according to claim 1, which is 1-(2'-cyanophenoxy)-2-hydroxy - 3 - (1'' - methylcyclohexylamino)-propane or a non-toxic, pharmaceutically acceptable acid addition salt thereof.

4. A compound according to claim 1, which is 1-(2'-cyan-5'-methylphenoxy)-2-hydroxy-3-(1'' - methylcyclopentylamino)-propane or a non-toxic, pharmaceutically acceptable acid addition salt thereof.

5. A compound according to claim 1, which is 1-(2'-cyan-5'-methylphenoxy)-2-hydroxy-3-(1'' - methylcyclohexylamino)-propane or a non-toxic, pharmaceutically acceptable acid addition salt thereof.

6. A compound according to claim 1, which is 1-(2'-cyan-5'-methylphenoxy)-2-hydroxy-3-(1'' - methylcycloheptylamino)-propane or a non-toxic, pharmaceutically acceptable acid addition salt thereof.

UNITED STATES PATENT OFFICE
CERTIFICATE OF CORRECTION

Patent No. 3,755,413

Dated August 28, 1973

Inventor(s) HERBERT KOPPE, WERNER KUMMER, HELMUT STAHL, KARL ZETTL,
ALBRECHT ENGELHARDT and WERNER TRAUNECKER

It is certified that error appears in the above-identified patent
and that said Letters Patent are hereby corrected as shown below:

Col. 4, line 16 - "alkoxyaryl" should read --alkoxyalkyl--.

Col. 8, line 38 - "methylcyclohexylamino" should read
--methylcyclopentylamino--.

Col. 9, line 2 - "hydroxymethylphe-" should read
--cyanophenoxyhy- --.

Col. 12, line 46 - insert --from-- after "more".

Signed and sealed this 29th day of October 1974.
